ANIMATED TOY

James A. Brown, 10712 Lockridge Drive,
Silver Spring, Md.

Filed Oct. 4, 1962, Ser. No. 71,991

Term of patent 14 years

(Cl. D34—15)

The egg-shaped tumbler shown in broken lines is for illustrative purposes only.

I claim:

The ornamental design for an animated toy, as shown and described.
